SHAKER

Earl S. Tupper, Upton, Mass.

Application December 24, 1952, Serial No. 22,860

Term of patent 14 years

(Cl. D2—3)

To all whom it may concern:

Be it known that I, Earl S. Tupper, a citizen of the United States and a resident of Upton, county of Worcester, and State of Massachusetts, have invented a new, original, and ornamental Design for a Shaker, of which the following is a specification, reference being had to the accompanying drawing forming a part thereof.

On the drawing:

Figure 1 is a top plan view;

Figure 2 is a front view in elevation; and

Figure 3 is a perspective view of a shaker, showing my new design.

I claim:

The ornamental design for a shaker, as shown.
EARL S. TUPPER.
